UNITED STATES PATENT OFFICE.

JOHN L. KASMAUSKAS, OF MATTAPAN, MASSACHUSETTS.

HYPODERMIC SYRINGE.

Application filed September 8, 1924. Serial No. 736,440.

To all whom it may concern:

Be it known that I, JOHN L. KASMAUSKAS, a citizen of the United States, and a resident of Mattapan, in the county of Suffolk and State of Massachusetts, have invented a new and useful Improvement in Hypodermic Syringes, of which the following is a specification.

My invention relates to hypodermic syringes and more especially to syringes of the type employed by dentists.

The principal objects of my invention are to provide a hypodermic syringe in which a medicine capsule may readily be inserted and from which it may conveniently be removed, and by means of which the stopper of the capsule will automatically be punctured by the act of securing said capsule in its holder.

20 In the drawings which accompany and form a part of this specification—

Figure 1 is a side view of a hypodermic syringe embodying my invention, the capsule holder being shown in closed position;

25 Fig. 2 is a central longitudinal section;

Fig. 3 is a central longitudinal section on an enlarged scale of the needle end of my improved syringe showing the capsule holder in open position;

30 Fig. 4 is a central longitudinal section on an enlarged scale of the head end showing the parts in the positions occupied when the capsule holder is open;

Figs. 5 and 6 are transverse sections taken 35 on the line 5—5 of Fig. 4, Fig. 5 showing the relative positions of the parts when the capsule holder is open, and Fig. 6 when the same is closed;

Fig. 7 is an end view of the head on an 40 enlarged scale.

In the particular drawings selected for more fully disclosing my invention 10 is a semi-cylindrical shell provided at its outer end with a disc 11 having a central bore 12, said disc constituting a capsule stop member, and provided at its inner end with a cylindrical head 13, said head and stop member preferably being formed integral with said shell.

45 Disposed concentrically about the shell 10 is a second semi-cylindrical shell 14 provided at the needle end of the syringe with a cylindrical portion 15 surrounding the capsule stop 11 and at its other end with a cylindrical portion 16 surrounding the head 13.

The two shells constitute a capsule holder and are relatively movable longitudinally and rotatively.

While various means may be employed 60 for governing the relative movement of the two shells, I prefer, as shown in the present instance, to effect this result by means of the pin 17 projecting from the head 13 and co-operating with the cam-slot 18 cut 65 into the sleeve or cylindrical end portion 16, said slot being so shaped that by giving the outer shell a half turn, the said outer shell will slide rearwardly along the inner shell and form therewith a cylinder for enclosing 70 the capsule, as shown in Figs. 1 and 2, the said cylinder preferably being not quite closed so that there will be two longitudinally-extending diametrically opposed slots 19 in the walls thereof through which the capsule 75 may be viewed. The outer shell is provided with a finger-piece 20 and the head with a knurled end 21, and the relative movement of the two shells may conveniently be effected by grasping the knurled end 21 with one hand and rotating the outer shell by means of the finger-piece with the other hand, after the capsule has been placed in the inner shell.

Passing through the head of the syringe is 85 a plunger 22 provided with a pointed inner end 23 for engaging the outer stopper 23' of the capsule and with a thumb-piece 24.

It is desirable to provide a slight degree 90 of friction between the plunger and the head, and in the present instance I employ a spring 25 disposed in an undercut recess in the head for this purpose, said spring engaging the walls of said recess, and the end portions 26, 26 embracing the plunger- 95 rod. The cylindrical end portion 15 of the outer shell is provided with a threaded extension for engagement with the socket 27 of the needle 28.

After the capsule 29 has been inserted in 100 its holder and one shell rotated with respect to the other in the manner above described, the stopper 30 is punctured by the needle, whereupon the depression of the plunger will eject the liquid from the capsule. Preferably the end of the capsule is flanged as shown at 31 in order to better retain the stopper and prevent the withdrawal of the same from the capsule, when the holder is opened by rotation of the outside shell in 110 the opposite direction.

After the holder has been opened and the

2
needle withdrawn from the stopper, said capsule may be removed from the holder by inverting and slightly shaking the latter.

Having thus described an illustrative embodiment of my invention without however limiting the same thereto, what I claim and desire to secure by Letters Patent is:—

1. A hypodermic syringe comprising a semi-cylindrical shell provided with a head at one end and with a capsule stop at the other, a second semi-cylindrical shell disposed circumferentially with respect to the first mentioned shell provided at one end with a cylindrical end portion surrounding said stop, and at the other end with a cylindrical portion surrounding said head, said shells being relatively movable longitudinally and rotatively, and means governing the movement of one shell with respect to the other.
2. A hypodermic syringe comprising a semi-cylindrical shell provided with a head at one end and with a capsule stop at the other, a second semi-cylindrical shell disposed circumferentially with respect to the first mentioned shell provided at one end with a cylindrical end portion surrounding said stop, and at the other end with a cylindrical portion surrounding said head, said shells being relatively movable longitudinally and rotatively, and a pin in said head

co-operating with a cam-slot in the cylindrical portion of the last mentioned shell.

3. A hypodermic syringe comprising a holder for a capsule having two relatively movable semi-cylindrical circumferentially-disposed members, a needle secured to one of said members and projecting into the same, and means whereby the relative rotative movement of said members will cause the longitudinal movement of said capsule and one of said members with respect to the other of said members and thereby effect the puncturing of one of the stoppers of the capsule by said needle.

4. A hypodermic syringe comprising a holder for a capsule having two relatively movable semi-cylindrical circumferentially-disposed members, a needle secured to one of said members and projecting into the same, and means whereby the relative rotative movement of said members will cause the longitudinal movement of said capsule and one of said members with respect to the other of said members and thereby bring said members into locked and closed relation and effect the puncturing of one of the stoppers of the capsule by said needle.

In testimony whereof, I have hereunto subscribed my name this sixth day of September, 1924.

JOHN L. KASMAUSKAS.
